R. A. Blair
Attorney

UNITED STATES PATENT OFFICE.

JAMES W. McCONNELL, OF WASHINGTON, DISTRICT OF COLUMBIA, ASSIGNOR TO THE GOVERNMENT OF THE UNITED STATES.

TORPEDO.

Application filed December 12, 1921, Serial No. 521,910. Renewed July 21, 1923.

To all whom it may concern:

Be it known that I, JAMES W. McCONNELL, a citizen of the United States, residing at Washington, District of Columbia, have invented new and useful Improvements in Torpedoes, of which the following is a specification.

This invention relates to improvements in torpedoes and more particularly to submarine torpedoes now in general use in the Navy.

Before stating the objects of the invention it is to be remarked that prior to putting torpedoes in general service they are subjected to several tests to determine their efficiency of operation, accuracy, etc. and it is often impractical to run the torpedo its full run, that is, perhaps 18,000 yards due to the limited area of the testing course. In these tests it is, therefore, often desirable to limit the run of the torpedo to the length of the course, that is, eight thousand and or ten thousand yards and at the end of the run recover the torpedo which, if satisfactory, is put into service. It frequently happens, however, that at the end of the run the buoyancy of the torpedo is such as to cause it to sink instead of to come to the surface which necessitates the dragging for the torpedo and sometimes without success.

It is impractical to put reduced charges of fuel and water into the torpedo to limit the run, as this causes a variation in the weight of the torpedo and its satisfactory working conditions under a full load cannot be as accurately determined.

It is, therefore, one of the main objects of the present invention to provide a torpedo with means for discharging the otherwise unused fuel and water from the torpedo system to reduce the weight of the torpedo and its contents at the end of a predetermined shortened run for the purpose of increasing the otherwise resultant buoyancy and thereby prevent the torpedo from sinking.

A further object is to provide a torpedo of the above general character with a simple and practical means for discharging the unused fuel and water which will be reliable and efficient in use and operation and prevent the inward flow of sea water into the torpedo at the end of its run.

With these objects in mind attention is

directed to the accompanying sheet of drawings showing such parts of the torpedo and the attachment therefor for accomplishing the above objects as will enable one skilled in the art to fully understand the same. 60

In these drawings,

Figure 1 is a transverse sectional view of a part of the torpedo taken through the attachment.

Figure 2 is a detailed sectional view of 65 part of the valve mechanism.

Referring now to the drawings in detail, 5 denotes the outer shell of the torpedo which is provided with openings 6 and 7 adapted to receive closing means engaging 70 threads 8 and carrying cylindrical strain-ers fitting the cavities 9. One of these cavities has inlet ports 10 through which water is fed from the water compartment. Normally this water passes through the compartment 9 in the strainer not shown and 75 out through the port 11 to the combustion flask. On the opposite side fuel from the fuel tank is fed into the port 12 through compartment 9 and strainer therein thence 80 out through port 13 to the combustion flask where it is ignited for the generation of heat. These parts are of well-known construction and require no detailed description. 85

The invention resides more particularly in applying at the ends of the chambers 9 outlet ports 14 and 15 connected by pipes 16 and 17 respectively with a valve carrying member 18 shown more in detail in 90 Figure 2. This valve carrying member is provided with two conical check valves 20 normally held in closed position by means of springs 21 reacting against a water orifice cap 22, which cap is provided with a 95 metered outlet opening 23 adapted to be closed by a plug screw 24 counter-sunk in the water orifice cup on a full length run. The size of the opening 23 regulates the wastage and consequently the length of the run, for obviously if the supply of fuel and water are exhausted, which supply the motive means for the turbines, the torpedo will stop. These parts are accessible through suitable openings in the torpedo shell. 100

These plug screws 24 are removed whereby leakage of a predetermined amount of water and fuel may take place through the pipes 16 and 17 and thence past the check valves 20. When a full or maximum run is de- 110

sired the plugs are, of course, positioned to prevent leakage at this point.

The orifices in the valve casing are retarded as desired whereby wastage, discharge of fuel and water may be regulated to bring the end of a full power torpedo run at a predetermined time. The strainers positioned in the chambers 9 prevent foreign matter from passing to the retarded openings and the check valves prevent the return flow of sea water into the torpedo system at the end of the run.

It is believed that the operation and use of this device will be clear to those familiar with the subject. In said runs the screw plugs 24 are removed and a predetermined portion of the fuel and water will pass out past the check valves 20 whereby at the end of a predetermined run the fuel and water will become entirely exhausted and the torpedo will stop and come to the surface due to its positive buoyancy. When the war shot is desired the plugs 24 are securely seated thus preventing the predetermined wastage of fuel and water and the torpedo will make its maximum run.

It will thus be seen that the present invention provides a simple and practical attachment for torpedoes, particularly adapted to insure the complete expulsion of water and fuel from the torpedo system and obtain the desired positive buoyancy whereby the torpedo will float at the end of the shortened run instead of sinking.

Without further analysis, the foregoing will so fully reveal the gist of this invention that others can by applying current knowledge readily adapt it for various applications without omitting certain features, that, from the standpoint of the prior art, fairly constitute essential characteristics of the generic or specific aspects of this invention, and, therefore, such adaptations should and are intended to be comprehended within the meaning and range of equivalency of the following claims.

What I claim is:—

1. In combination with a torpedo provided with passages for fuel and water to the combustion flask, by-passes leading therefrom and communicating with openings in the exterior of the torpedo whereby the contents of the fuel and water system will be

exhausted at the end of a predetermined shortened run.

2. In combination with a torpedo provided with passages for fuel and water to the combustion flask, by-passes leading therefrom and communicating with the exterior of the torpedo whereby the contents of the fuel and water system will be exhausted, said by-passes being provided with stop valves to prevent the inflow of the water at the end of the run.

3. In combination with a torpedo provided with passages for fuel and water to the combustion flask, by-passes leading therefrom and communicating with the exterior of the torpedo whereby the contents of the fuel and water system may be exhausted as desired, said by-passes being provided with valves to prevent the inflow of the water at one end and means for closing said valves entirely as and when desired.

4. In combination with a torpedo, chambers through which the fuel and water are adapted to pass to the combustion flask, by-passes from said chambers communicating with the exterior of the torpedo and means for preventing the inflow of water from the sea to said by-passes.

5. In combination with a torpedo, chambers through which the fuel and water are adapted to pass to the combustion flask, by-passes from said chambers communicating with the exterior of the torpedo, means for preventing the inflow of water from the sea to said by-passes, said means including spring actuated check valves provided with openings through which the water and fuel may pass and means for closing said openings.

6. In combination with a torpedo provided with passages for fuel and water to the combustion flask, by-passes leading therefrom and communicating with openings in the exterior of the torpedo whereby the contents of the fuel and water system will be exhausted at the end of a predetermined shortened run, said openings being metered whereby rate of wastage may be controlled for varying length of shortened runs.

Signed at Alexandria, Va., this seventh day of November, 1921.

JAMES W. McCONNELL.
